UNITED STATES PATENT OFFICE.

SAMUEL DRESNER, OF CHICAGO, ILLINOIS.

DESIGN FOR A BELT.

SPECIFICATION forming part of Design No. 33,893, dated January 8, 1901.

Application filed December 8, 1900. Serial No. 39,236. Term of patent 3½ years.

To all whom it may concern:

Be it known that I, SAMUEL DRESNER, a citizen of the United States, residing at Chicago, in the county of Cook and State of Illinois, have invented and produced a new and original Design for Belts, of which the following is a specification, reference being had to the accompanying drawings, forming part thereof.

10 Figure 1 is a front view in elevation of a belt, showing my new design; and Fig. 2 is a plan or edge view thereof.

As shown in the drawings, the leading or material feature of my design consists of a piece A, having near one of its ends on the outer surface a strap B, pointed at both of its ends, and one end of said strap being free from the piece A, which forms the main portion of the belt. The piece B is formed with 15 an opening C, which is slightly contracted, as at c, near its front end. The rear portion of said opening is somewhat circular, and near the rear portion of this opening the portion B is provided with a loop C', slightly raised or extended outwardly. On the opposite portion of the piece A is another strap D, having both of its ends pointed, but its front end somewhat narrower than the rear one. The edges of the piece or strap D are formed with circular recesses d, which are located opposite each other.

Having described my invention, what I claim as new, and desire to secure by Letters Patent, is—

The design for a belt, substantially as here- 35 in shown and described.

In testimony whereof I have signed my name to this specification in the presence of two subscribing witnesses.

SAMUEL DRESNER.
